UNITED STATES PATENT OFFICE.

EDWARD FRYE, OF DORCHESTER, MASSACHUSETTS.

COMBINED FUSE AND SWITCH BOX.

1,173,791.

Specification of Letters Patent. Patented Feb. 29, 1916.

Application filed May 19, 1915. Serial No. 29,081.

To all whom it may concern:

Be it known that I, EDWARD FRYE, a citizen of the United States, residing at Dorchester, in the county of Suffolk and State of Massachusetts, have invented certain new and useful Improvements in Combined Fuse and Switch Boxes, of which the following is a specification.

This invention relates to combined switch and fuse boxes, and has particular reference to devices of this character adapted for outside installation, as, for example, on a pole carrying service wires.

The object of the invention is to provide a simple, practical and efficient safety device of this kind, whereby the fuse plug may be entirely disconnected from the line whenever it is necessary to remove the same for renewal or repairs, thus eliminating all danger to the operator.

The invention contemplates the use of an oil switch for disconnecting the fuse from the line, such switch being operated by means of an insulated handle outside of the box.

In order that the invention may be clearly understood, reference is had to the accompanying drawing, forming a part of this specification, and in which,

Figure 1 is a front elevation of my improved combination box complete, showing the method of connecting the line wires thereto; Fig. 2 is a vertical transverse section through the same; Fig. 3 is a horizontal section taken on a plane just below the cover, parts being in plan; Fig. 4 is a transverse section through the fuse compartment of the box; Fig. 5 is a similar section through the switch compartment; Fig. 6 is an enlarged fragmentary, horizontal section through one side of the fuse compartment showing structural details; and, Fig. 7 is a fragmentary perspective view of the outer end of the switch shaft and associated parts.

My improved combination switch and fuse box is preferably formed throughout of porcelain or similar material, and is all in one piece except the cover. The box is designed to be interposed in a transmission line, at the point where house wires are connected thereto, or elsewhere, and is particularly adapted to be mounted upon the cross-arm of a transmission pole, or other suitable support.

Referring to the drawings in detail, the improved box is designated in its entirety

by the reference character 1, and comprises end walls 2 and front and rear side walls 3, as well as a partition wall 4, dividing the box into switch and fuse compartments. 60 The switch compartment is open at the top, and has a closed bottom 5, while the fuse compartment is closed at the top, as indicated at 6, and has an opening 10 formed through the bottom thereof. The cover 7, 65 preferably having a rounded top, so as to shed water, is secured to the box so as to close the switch compartment. The cover 7 may be provided with a peripheral flange 8, arranged to fit over the walls of the box, 70 and may be held in position by means of bolts 9. The front wall of the fuse compartment is provided with an opening 11, adapted to be normally closed by a fuse plug 12, having a handle 13, and a flange 13^a serving to tightly cover the opening 11. Each end wall 2 of the box is preferably provided with a boss 14, to receive the line wires, and with perforated lugs or ears 15, by means of which the box is secured to a cross-arm 80 or other support.

The leading-in conductor is indicated at 16, and may be of the usual construction, consisting of a copper core covered by a layer of insulation. The bare end of this 85 conductor extends through the wall of the box and is connected inside the switch compartment with a clip 17. The switch which I employ comprises a switch blade 18, made of copper or similar material, and secured 90 at one end to an insulating block 19, rigidly mounted upon a shaft 20, journaled at one end in an interior boss 21, carried by the rear wall of the box and extending at its other end through the front wall, and a 95 similar boss 22, formed on the outside thereof. The block 19 and shaft 20 may conveniently be made of hard fiber. An operating handle 25 is secured to the extended end of the shaft 20, and means are preferably provided for resiliently holding the handle and switch blade in either the off or on position. Such means consist of a pair of grooves or notches 23, formed in the outer face of the boss 22, and a light spring 100 24, secured to the underside of the handle 25 and adapted to snap into one or the other of the notches as the handle is moved.

The switch blade 18 fits snugly between and in frictional engagement with the arms 110 of the bifurcated extended end of clip 17, and is adapted to engage at its free end with

a contact 26, mounted near the bottom of the box, and secured to the partition wall 4 by means of a bolt 27. As clearly shown in Figs 2 and 3, this bolt 27 extends through 5 the partition wall 4 into the fuse compartment and connects, in such compartment, with a bracket 29. It will be understood that the bolt 27 is suitably packed so as to fit oil-tight in the wall 4, to prevent leakage 10 of oil into the fuse compartment. Oil is placed in the switch compartment, as indicated at 28 in Fig. 2, and is maintained at such a height that the lower end of the switch blade 18 is always well submerged. 15 By this means dangerous arcing at the contact 26, when the switch is moved to break the circuit, is prevented.

The bracket 29 is L-shaped, as shown, and carries a resilient spring clip 30. A similar 20 bracket 35 is located on the opposite wall of the fuse compartment, and may conveniently be held in position by serving as a nut for the screw-threaded end 37 of the outgoing conductor 36. This conductor 36 is 25 received in a socket formed in the boss 14, and has a shoulder 38 which limits its inward movement. By screwing up the conductor, therefore, the bracket 35 is firmly clamped against the wall of the box. A 30 construction similar to this may be employed for connecting the conductor 16 to the clip 17. The bracket 35 carries a spring clip bent to form a pair of spaced resilient arms 34, as clearly shown in Fig. 6. This 35 clip is secured to the bracket 35 by means of a bolt or rivet 39, and is identical in construction with the clip 30 above referred to. The fuse plug 12 consists of a relatively thin, flat body of insulating material, such 40 as porcelain, preferably tapering in form as shown in Fig. 4, and has mounted near its outer end on opposite sides and adjacent opposite edges thereof, a pair of clips 31 and 32. These clips are identical in construction, 45 and as shown in Fig. 6, each preferably has its end bent back upon itself as indicated at 33 to form a rounded head. Such rounded heads or ends of the clips 31 and 32 are adapted to enter between the spring arms 50 of the clips 30 and 34, respectively, as shown generally in Fig. 3, and more in detail in Fig. 6. The frictional engagement of these clips is sufficient to hold the fuse plug in position. The fuse itself, which is composed 55 of the usual alloy, is indicated at 12°, and is secured at its ends to clips 31 and 32. The middle portion of the fuse passes through a notch or opening 12° in the body of the fuse plug in such a manner that half of the 60 fuse is disposed on one side of the plug and half on the other. In this way, danger of arcing or flashing-over is minimized. If the fuse should burn out, the products of combustion will be discharged downwardly 65 through the opening 10, and thus do no

harm. The line wires are connected to the conductors 16 and 36 by means of couplings 40, of any suitable construction.

In practice, whenever it is necessary to remove the fuse plug for inspection or repair, the operator swings the handle 25 to the left, as shown in Fig. 1, thus breaking the circuit at the contact 26 and absolutely disconnecting the fuse plug and associated parts from the power side of the line, and 70 making it perfectly safe to handle the same. Moreover, the arc is produced in the switch compartment where it is extinguished by the oil, rather than at the clips 31 and 32. It will be seen that the entire device is simple, 75 compact and practical in its operation, and it is thought that its many advantages will be fully appreciated without further discussion.

It will, of course, be understood that two 80 or more switch blades may be mounted on the shaft 20, if desired, and a corresponding number of fuses employed.

What I claim is:

1. A combined fuse and switch box having two vertically extending compartments arranged side by side, a switch blade pivotally mounted in the upper part of one compartment, and depending therein, said compartment being open at the top only 95 and adapted to contain oil, a contact mounted on the wall of said compartment near the bottom thereof, and arranged to be engaged by the depending portion of said switch blade below the oil level in said compartment, a pair of clips in the other compartment, one of which is connected with said contact, a fuse plug held in said clips, such other compartment being closed at the top and open at the bottom, and means for forming exterior electrical connections with said switch blade and fuse plug.

2. In a device of the character described, the combination with a receptacle having a partition wall dividing the same into two compartments, of a switch in one compartment, said compartment containing oil, and provided with a removable cover, and the other compartment having an opening through its side, a fuse plug fitting into 110 and closing such opening, a fuse carried by said plug in said last mentioned compartment, and means for connecting said switch and fuse in a series circuit.

3. In a device of the character described, the combination with a receptacle having outer walls and a partition wall dividing the same into two compartments, of a switch blade pivotally mounted in one compartment, a contact carried by the partition wall 120 and adapted to be engaged by said switch, a pair of clips in the other compartment, one of said clips being mounted on said partition wall and electrically connected with said contact, and the other clip being mount- 125

ed on the outer wall opposite said partition wall, and a fuse plug in said last mentioned compartment, said plug having a fuse provided with terminals adapted to simultaneously engage said clips, and means for forming exterior electrical connections with said switch blade and outer clip, respectively.

4. In a device of the character described, a box comprising front and rear side walls and end walls, and a vertical partition wall parallel with said end walls dividing the box into two compartments, lugs carried by said end walls whereby the box may be secured with its rear wall against a suitable

support, a switch in one compartment, and 15 a handle for operating the switch projecting through the front side wall, and a fuse plug in the other compartment, said front side wall being provided with an opening through which said plug may be inserted 20 and removed.

In testimony whereof I have affixed my signature in presence of two witnesses.

EDWARD FRYE.
